PLLC; Richard S. Myers, Jr.

(57) **CLAIM**

The ornamental design for an ironing board lock, as shown and described.

DESCRIPTION

FIG. 1 is a top perspective view of the design of an ironing board lock showing the new design;

FIG. 2 is a front elevation view of the ironing board lock shown in FIG. 1;

FIG. 3 is a rear elevation view of the ironing board lock shown in FIG. 1;

FIG. 4 is a left side elevation view of the ironing board lock shown in FIG. 1 (the right side elevation view of the ironing board lock is a mirror image of the view shown in FIG. 4);
FIG. 5 is a top plan view of the ironing board lock shown in FIG. 1;

FIG. 6 is a bottom plan view of the ironing board lock shown in FIGS. 1; and,

FIG. 7 is a perspective view of the ironing board lock shown in FIG. 1 illustrating the ironing board lock attached to an ironing board.

The broken lines shown in the drawing views are included for the purpose of showing environmental structure that forms no part of the claimed design.

1 Claim, 4 Drawing Sheets
